UNITED STATES PATENT OFFICE.

JOHN BRICKEN, OF CHICAGO, ILLINOIS.

CARBURETER.

1,178,127.

Specification of Letters Patent.

Patented Apr. 4, 1916.

Application filed December 14, 1914. Serial No. 877,054.

To all whom it may concern:

Be it known that I, JOHN BRICKEN, subject of Russia, residing at Chicago, in the county of Cook and State of Illinois, have 5 invented a certain new and useful Improvement in Carbureters, of which the following is a full, clear, concise, and exact description.

My invention relates to a carbureter for 10 internal combustion engines and its object is to provide simple and efficient means by which a liquid fuel is converted into vapor and mixed with air to form the engine-charge.

15 A further object is to provide in a carbureter automatically operating means by which the desired proportion of air and gaseous fuel are automatically maintained, the amount of fuel supplied being automatically regulated by the flow of air through the carbureting chamber.

With the above objects in view, my invention provides means whereby the liquid is fed upon a revolving plate, the liquid 25 tending to be held upon said plate by adhesion and being thrown therefrom by centrifugal force.

My invention and the several features thereof may be more readily understood by 30 reference to the accompanying drawings, in which—

Figure 1 is a longitudinal, central section of a carbureter embodying my invention; Fig. 2 is a transverse section on the line 2—2 of Fig. 1; and Fig. 3 is an enlarged, detailed 35 plan view of the lower end of a spacing tube which communicates with the feed tube.

Like numerals of reference refer to like 40 parts throughout the several views.

Referring to the drawings, the air supply 45 chamber 1 of the carbureter is supplied with gasolene or other suitable liquid fuel from the tank or fuel supply chamber 2, said chambers being in communication through the feed duct 3 of which the feed tube 4 is a continuation. The upper end of the tube 4 communicates with a conical depression 5 in the center of the upper surface of a revolving disk 6. The disk is arranged with 50 its upper surface in a horizontal plane and is mounted to freely revolve upon the tube 4, said disk being preferably provided with a downwardly extending sleeve 7 which surrounds the tube 4. The disk 6 is caused to

revolve by a series of vanes or blades 8, said 55 vanes being preferably secured to and projecting from the disk 6, as shown in the drawings. The air suction through the chamber 1 causes the vanes 8 to rotate, thus imparting a rotary motion to the disk 6. 60 The speed of rotation of said disk is thus dependent upon the current of air flowing through the chamber 1. Such flow of air may be controlled in the usual well known manner.

I preferably provide, immediately above the disk 6 and suitably spaced therefrom, a member 9 having at its lower end a circular, plane surface which extends parallel to the upper surface of the disk 6. The opposing 70 surfaces of the disk 6 and the member 9 thus provide, as it were, a nozzle having a contracted, circular passage, the oil tending to adhere to the two opposing surfaces. The member 9 forms the hub portion of an annular ring 10, which ring is threaded upon the interior of the casing of the chamber 1, whereby the member 9 may be vertically adjusted to properly space apart the disk 6 and the member 9. Threaded through the member 9 is a tube 11 which is so adjusted that it bears down upon the upper surface of the disk 6. The tube 11 projects below the end of the member 9 and serves as a spacing block for separating the disk 6 from the member 9, thereby preventing the disk 6 from rising under the action of the revolving blade 8. At its lower end the tube 11 is provided with one or more grooves or notches 12, through which the liquid fuel may escape into the 85 space between the disk 6 and the opposing surface of the member 9. Extending through the tube 11 is the stem 13 of a needle-valve of the usual construction, which valve can be adjusted to control the flow of 90 the liquid from the feed tube 4.

The fuel tank 2 may be provided with the usual float 14 which controls, in a well known manner, the valve 15, thereby maintaining a predetermined fluid level in the 100 tank 2. The level of the fluid in the tank 2 is preferably maintained slightly lower than the upper surface of the disk 6, in order that when the engine is not running the oil will not flow from the pipe 4 onto the surface of the disk 6. Upon a rotary motion being imparted to the disk 6, the centrifugal force exerted upon the liquid in the cavity 105

5 will cause the liquid to flow through the openings 12 upon the upper surface of the disk 6. The liquid fuel which is thus fed into the narrow space between the opposing 5 surfaces of the disk 6 and the member 9 tends, through adhesion, to remain between said two opposing surfaces. However, the rotation of the disk 6 causes the liquid to be thrown out, by centrifugal force, in the form 10 of a fine spray or vapor, which becomes thoroughly mingled with the air passing through the carbureter 1. The amount of liquid fuel discharged into the chamber 1 is thus dependent on centrifugal force, 15 which in turn is proportional to the speed of rotation of the disk 6, which in turn is proportional to the amount of air passing through the carbureter chamber. The proportion of fuel to air in the engine charge is 20 thus automatically maintained constant.

It is obvious that changes in the details of structure shown and described may be made without departing from the scope of the invention as defined in the accompanying 25 claims.

So far as I am aware, I am the first to provide means by which centrifugal force is utilized for discharging liquid fuel in the 30 form of a spray into the carbureting chamber of an internal combustion engine.

What I claim is:—

1. In a carbureter, the combination of an air chamber, a rotatable member, an opposed member having adjacent parallel surfaces and means for separating said members to provide a nozzle opening outwardly 35 in all directions without obstruction.

2. In a carbureter, the combination of an air chamber, a rotatable plate, having a central opening, a hollow supporting shaft therefor, a feed tube, said shaft and feed tube being concentrically mounted and means mounted on said shaft for rotating said plate.

3. In a carbureter, the combination with an air chamber; of a fuel-discharge nozzle disposed within said chamber, said nozzle comprising two members having adjacent parallel surfaces, said members being relatively 40 rotatable and one of them being provided with vanes adapted to be actuated by the air which passes through said chamber.

4. In a carbureter, the combination with an air chamber; of a fuel-discharge nozzle 45 disposed wholly within said chamber, said nozzle comprising a revolute member and an opposed stationary member; and means, actuated by the air passing through said chamber, for rotating said revolute member.

5. In a carbureter, the combination with an air chamber; of a fuel-discharge nozzle 50 disposed within said chamber, said nozzle comprising a revolute member and a member spaced therefrom to provide a clearance;

the adjacent faces thereof having substantially the same outline, and means, actuated by air passing through said chamber for rotating said revolute member.

6. In a carbureter, the combination with 70 an air chamber; of a fuel-discharge nozzle disposed within said chamber, said nozzle comprising a revolute plate and an opposed member; and vanes carried by said revolute plate.

7. In a carbureter, the combination of an air chamber, a vertically disposed fuel-supply tube located centrally of said chamber, a rotatable member mounted about the open end of said tube, vanes carried by said rotatable member, and a stationary member opposed to said rotatable member, said two members constituting a fuel-discharge 80 nozzle.

8. In a carbureter, the combination of an air chamber, a vertically disposed fuel-supply tube located centrally of said chamber, a rotatable member mounted about the open end of said tube, vanes carried by said rotatable member, a member opposed to said 90 rotatable member and adjustable toward and from the latter, and an adjustable spacing tube projecting from the adjustable member against the central upper surface of said rotatable member, said tube having 95 openings therein for the discharge of fuel into the space between said opposing members.

9. In a carbureter, the combination of an air chamber, a fuel-supply tube located 100 within said chamber, a rotatable member mounted about the open end of said tube, vanes carried by said rotatable member and a member opposed to said rotatable member and adjustable toward and from the 105 latter.

10. In a carbureter, the combination of an air chamber, a fuel-supply tube located within said chamber, a rotatable plate having a central opening communicating with 110 said tube, a supporting shaft for said rotatable plate, said shaft and feed tube being concentrically mounted, means on said shaft for rotating said plate and a needle valve for varying the effective size of said opening. 115

11. In a carbureter, the combination of an air-chamber, a rotatable plate, a hollow supporting shaft therefor, a feed tube, said shaft and tube being concentrically mounted, and means mounted on said shaft for rotating said plate. 120

12. In a carbureter, a fuel nozzle consisting of two elements having opposed surfaces, one of which is rotatable, means for adjusting the distance between said surfaces 125 and an adjustable needle valve to control said nozzle.

13. In a carbureter, the combination with an air chamber, of a fuel discharge nozzle 130 consisting of a pair of members spaced

apart to provide an unobstructed peripheral passage, one of said members being rotatable and means for adjusting said members relatively to each other to vary the size of 5 said passage and thereby control the fuel supply.

In witness whereof, I hereunto subscribe

my name this 12th day of December, A. D., 1914.

JOHN BRICKEN.
